PURIFICATION OF HYDROCARBONS

Harold J. Hepp and Howard R. Sailors, Bartlesville, Okla., assignors to Phillips Petroleum Company, a corporation of Delaware

Application December 17, 1945, Serial No. 635,590

5 Claims. (Cl. 260—674)

1

This invention relates to the treatment of hydrocarbons. In one of its more specific aspects it relates to a method for the purification of benzene and its homologues.

Benzene and its lower alkyl homologues have long been products of commercial importance. The destructive distillation of coal has been and is a major source of such compounds. In more recent years, the cracking of petroleum has provided another source of these compounds, and the products of this operation at least much of the time contain benzene and alkyl benzene compounds in recoverable amounts.

Fractionation, with or without combination with such other process steps as absorption, is used as a means of recovery and separation of these compounds from the cracked products. Such methods, however, do not readily yield pure products. Olefins, produced in large amounts by cracking of petroleum, are especially difficult to separate from aromatic compounds by such means, and, consequently, the aromatic compounds separated from mixtures of aromatics and olefins contain excessive amounts of olefins for many uses. Treatment with sulfuric acid has been used for removing the olefins from these mixtures, although such side reactions as sulfonation leaves much to be desired in this method. Solid aluminum chloride has also been used as a treating agent in the removal of the olefinic impurities from benzene and its lower alkyl homologues with satisfactory removal of the olefins.

One object of our invention is to provide a process for the treatment of hydrocarbon stocks containing benzene for the production of a pure benzene product.

Another object of our invention is to provide a process for the removal of olefins from benzene stocks by the use of aluminum chloride-hydrocarbon complexes.

Still another object of our invention is to provide a process for the removal of olefins from benzene and its lower alkyl homologues by the use of aluminum chloride-hydrocarbon complexes with the simultaneous recovery of HCl from the aluminum chloride used.

Still other objects and advantages of our process will become evident to those skilled in the art from a careful study of the following description which when taken in conjunction with the accompanying drawing forms a part of this specification.

We have discovered that AlCl₃-hydrocarbon complexes, including those formed and used in

2

other processes and now discarded as waste products such as the excess catalyst from alkylation or isomerization processes, may be used as treating agents in the removal of olefinic impurities from benzene and its lower alkyl homologues; and that at least a portion of the chlorine in the complex can be recovered as HCl in the process.

Aluminum chloride is widely used as a catalyst in hydrocarbon conversion processes. The AlCl₃ is used much of the time as a hydrocarbon complex, part of the time formed in situ from solid anhydrous AlCl₃, and part of the time the complex is manufactured outside the reaction zone and then charged to the reaction zone. In the operation of such processes, spent complex is discarded as a waste product, and even the disposal of this waste complex becomes at times a problem. The usual disposition is by burning or hydrolysis in water.

When anhydrous aluminum chloride is used in the treatment of paraffinic, olefinic, cyclic, or aromatic stocks aluminum chloride-hydrocarbon complexes are usually formed. We have found when such complexes are spent as regards further use in said processes that these complexes are useful for treating processes such as herein disclosed.

Suitable treating agents for our process include fluid complexes formed by reacting AlCl₃ with paraffinic, olefinic, cyclic, or aromatic hydrocarbons. Such complexes usually contain in excess of 40 per cent by weight of AlCl₃ and react vigorously with evolution of heat when shaken with water. The heat released usually is in excess of 280 calories per gram.

We have found that when such complexes are agitated with aromatic concentrates, as, for example, close-boiling benzene, toluene, xylene, etc., fractions separated from the products formed when petroleum fractions are treated by thermal or catalytic cracking processes, or obtained from coke-oven products or other suitable sources, any olefins and diolefins present are caused to polymerize to high-boiling substances readily separated from the aromatics by simple distillation, and/or react with the aromatics to form high-boiling alkylated aromatics. To promote the polymerization and minimize the alkylation it is preferred to use AlCl₃-hydrocarbon complexes which are not too active, for example complexes having a heat of reaction in water of not above about 400 calories per gram. If desired, HCl, H₂O, CH₂Cl, etc., may be used in amounts of 0.1 to about 5 per cent based on the aromatic concen-

trate charged to a unit to increase the speed of the reactions, since such substances have a powerful promoting action on the AlCl_3 -hydrocarbon complex.

The aromatic concentrate derived from any suitable source is contacted with the aluminum chloride-hydrocarbon complex in suitable apparatus consisting of at least one contactor and operated in substantially liquid phase, temperature being suitably regulated. In this contacting operation, the olefin is converted to high-boiling material readily separated from the aromatic compounds in the treated concentrate by such means as fractionation.

The recovery of HCl is made possible by the fact that the addition of water to AlCl_3 -hydrocarbon complex leads to a hydrolysis reaction in which HCl is released and oxygen-containing aluminum compounds are formed.

The solubilities of complex in benzene and benzene in complex are rather high. For example, at room temperature, an AlCl_3 -hydrocarbon complex withdrawn from an ethylene-isobutane alkylation process increases in volume to about 2.5 to 3 times its original volume upon treating olefin-containing benzene. The benzene, in turn, will dissolve between about one to three per cent of its own volume of complex. It is, therefore, necessary to consider these mutual solubilities in designing apparatus for carrying out the process of this invention with best results.

Referring now to the drawing and specifically to Figure 1, a raw aromatic stock such as a benzene stock containing olefins is conducted through a pipe 10 to a mixer 11, the mixer operating in substantially liquid phase between the temperatures of about 40° F. and 250° F., preferably between about 100° F. and 175° F., the pressure being at least sufficient to maintain the benzene stock in the liquid phase. Aluminum chloride-hydrocarbon complex from a subsequent step may be introduced to the mixer 11 through a pipe 19. HCl , water to generate HCl , or other activator from any source may be introduced to the mixer 11 through a pipe, not shown. The raw benzene and complex are thoroughly mixed by a mechanical agitator. The reaction mixture of complex and hydrocarbon may be conducted from the mixer 11 through a pipe 12 to a settler 13. In this settler the hydrocarbon and complex are allowed to separate by gravity, the hydrocarbon phase being the upper phase. The hydrocarbon phase is removed from the separator 13 through a pipe 14 and passed to a second mixer 16. Fresh complex, from a source not shown, for treating the benzene, is added through pipe 15 to pipe 14 and carried to mixer 16. In this mixer the hydrocarbon and added complex are thoroughly mixed, the temperature and pressure limitations of mixer 11 applying also to this mixer. In this mixer substantially complete reaction of olefin and partial spending of the newly added complex is obtained. Reaction mixture of complex and hydrocarbon are withdrawn through a pipe 17 to a gravity settler 18, operating in the same manner as the settler 13. The settled complex from this settler is recycled through pipe 19 to the mixer 11, as mentioned herein before.

The hydrocarbon phase from settler 18 is passed through a pipe 20 to a pump 21, then through a discharge line 22 into a tank 23. Water may be added through a pipe 24 to this tank 23 and/or through a pipe 25 to the transfer pipe 20. Settlings from the bottom of the settler tank 23 are withdrawn through a recycle pipe 26 and

added to line 20. Spent complex is removed from the settler tank 13 through a pipe 27 and added to this pipe 26, thereby joining the recycle stream from the tank 23. In this tank and pump system the aluminum chloride complex reacts with the water and is decomposed, the amount of water added being such that it is substantially completely consumed in the complex decomposition, and the complex is intended to be decomposed substantially completely. We prefer to use not more than about three moles of water per mole of active AlCl_3 . It is preferred that the recirculation stream carried by pipe 26 be comparatively large so that the heat evolved by the reaction of the water and complex does not lead to a large localized temperature rise as in pump 21. Cooling of the tank 23, though not shown, may if necessary be accomplished by a heat exchanger in line 22 or by internal cooling within the tank itself. From the tank 23 the mixed product is removed through a pipe 30 to a stripper 32, this product containing the oils from the complex, benzene, and alkylated benzene as the major portion of its hydrocarbon constituents, and hydrogen chloride and some aluminum compounds from the hydrolysis of the aluminum chloride in the complex. Solids may be removed if desired by any conventional means, for example, by a sand filter 30a prior to stripping. Tank 23 should preferably be of such size that the stream carried by pipe 30 is low in solids, the major portion of the solids in the tank being carried in suspension in the lower part of the tank to be removed through pipe 26. From the pipe 26 a part of the material passing therethrough is removed through a pipe 28 to a gravity settler 29 where at least a part of the solids and heavy materials is allowed to settle. The upper phase from this settler 29 is carried by a pipe 31 to pipe 30, thence through sand filter 30a, into the stripper 32. In this stripper 32 HCl is removed as an overhead product through pipe 33 while the hydrocarbons are removed through the bottoms line 34 and passed to further purification steps such as, for example, a water and/or a caustic wash and fractionation steps. From the settling tank 29 the lower phase containing the major portion of the solids is removed through a draw-off line 35 and added to the contents of pipe 34. The hydrogen chloride from the overhead line 33 may be treated for removal of hydrocarbons and other contaminants by oil absorption, adsorption in charcoal or silica gel or by other means.

The reactions taking place in the two mixers 11 and 16 and system of pump 21 and tank 23 are exothermic and it is therefore desirable to provide some means of temperature control at these points. Numerous methods of temperature control, for example, recirculation through a heat exchanger or internal cooling are well known and need not be discussed in detail.

Figure 2 of the drawing shows a second embodiment of our invention. Olefin containing benzene stock is charged through a charge line 36 to a mixing pump 37, thence through a line 38 into a settling tank 39, operating in substantially liquid phase. This tank 39 contains substantially spent catalyst and hydrocarbon and is sufficiently large to serve as a gravity separator. The aluminum chloride containing complex is withdrawn from tank 39 and passed through a pipe 40 to the charge line 36 up stream of the pump 37, at which point the complex is contacted with the fresh benzene olefin containing stream.

5

Partially spent complex from a subsequent source passes through pipe 47 to pipe 48 and is contacted with fresh benzene charge in the pump 37. In this pump 37 the aluminum chloride complex is substantially completely spent in reacting with olefins from the raw benzene stock. From tank 39 the hydrocarbon or upper phase, still containing a substantial amount of olefins, is removed through a pipe 41 and conducted to a mixing pump 42. Fresh aluminum chloride complex from a drier 68 is passed through a pipe 71 and added to the partly treated benzene stream in line 41, these materials being thoroughly mixed or contacted in the mixing pump 42. The mixture is passed through a pump discharge line 43 to a second settling tank 44 which operates in about the same manner as tank 39. Settled complex from the lower portion of tank 44 is withdrawn through a pipe 45 and returned to pipe 41 at a point upstream of the pump 42. The amount of this recycled stream should preferably be sufficiently large to prevent an excessively large temperature rise due to reaction of olefins and complex in the pump 42. In this portion of the system, that is, pump 42 and tank 44, the olefins remaining from the previous contacting are substantially completely removed and the complex partially spent. This double operation of the two mixers and their respective settling tanks is substantially a countercurrent operation.

A portion of the recycled complex stream from pipe 45 is withdrawn therefrom and passed through a pipe 47, previously mentioned, to pipe 40, this recycled complex then following a path as described.

The hydrocarbon phase in the tank 44 is removed through an outlet pipe 46 and passed to a sand filter 48 in which suspended complex is separated and returned through a pipe 49 to the complex stream in the pipe 45. The hydrocarbon phase is removed from the sand filter through an outlet pipe 50 and passed to a water and/or caustic washer 51, then out pipe 52 to further treatment, not shown.

From the pipe 40 a portion of the substantially spent complex from the settler 39 is withdrawn and led by a pipe 53 to a gravity settler 54, the hydrocarbons separating and forming an upper phase in this settler and being conducted by a pipe 55 back to the benzene charge stock line 36 as a recycle stream. The complex phase in the settler 54 is withdrawn and passed through a pipe 56 to a mixing pump 60. When desired, at least a portion of this latter stream may be by-passed from pipe 56 through a pipe 57 to a pipe 66 and to join a hydrocarbon stream in pipe 50 just prior to passage of the hydrocarbon stream into the water or caustic washer 51. The settler 54 may also be by-passed by passing the substantially spent complex from pipe 53 through a pipe 58 to pipe 56 and thence to the mixing pump 60. Water from a line 59 is introduced into the complex passing through pipe 56 and this mixture thoroughly mixed and contacted in the mixing pump 60. The water is added in such proportion that the active complex is at least partially decomposed, and the water is substantially completely consumed in the decomposition reaction. As in the previous illustration, that is, the embodiment of Figure 1, the water is added at the rate of about 1 to 3 moles per mole of active aluminum compound. From this mixing pump 60 reaction mixture consisting of aluminum compounds, hydrogen chloride and hydrocarbon is conducted by a pump outlet line 61 to a sepa-

6

rating tank 62 which is operating in such manner as to provide a vapor space in the upper portion of the tank. We prefer to operate this tank at temperatures above about 100° F. in order to reduce the solubility of the hydrogen chloride in the liquid hydrocarbons. The hydrocarbon liquid from this tank is withdrawn through a pipe 63 and added to the complex in pipe 56 as a recycle stream prior to passage of the complex through the pump 60 so that any water remaining in the tank 62 will be consumed. A sufficiently large volume of the liquid in the tank 62 is recycled to absorb heat released by the hydrolysis reaction in pump 60 to prevent an excessive temperature rise at this point.

The hydrogen chloride accumulating in the vapor space of tank 62 is conducted through a pipe 67 to the drier 68 in which the HCl is dried by countercurrent contacting with fresh complex added to the drier through a complex charge line 69. Dry hydrogen chloride is removed through a pipe 70 and conducted to suitable storage or utilization, not shown. A portion of the hydrogen chloride may be passed through a pipe 73 and recycled to the pipe 40 as an activator for the substantially spent complex for treating the raw benzene charge stock. From the drier 68 complex is removed and passed through the pipe 71 and added to pipe 41 which is upstream of the mixing pump 42.

A portion of the hydrolyzed complex from settling tank 62 which is carried by recycle line 63 is removed through a pipe 64 and passed to a settler 65 in which insoluble aluminum compounds are allowed to settle and these are subsequently removed through a discharge pipe 72 for such disposal as desired. The liquid from the upper portion of this settler is removed through an overhead pipe 66, and after addition of settling from settler 54 to line 66 by way of pipes 58 and 51, the mixture passes on to pipe 50 as mentioned hereinbefore. At any time desired the settler 65 may be by-passed by the use of a by-pass 74 and the hydrolyzed materials passed therethrough are then passed directly to pipe 50 prior to the water and/or caustic wash treatment in the treater 51.

Figure 3 shows an alternative treatment of the aluminum chloride complex phase without hydrogen chloride recovery. In this embodiment our invention is shown with reference to such a mixer system as mixers 11 and 16 of Figure 1. Substantially spent complex is withdrawn from the settler 13 and passed through a pipe 75 to a mixing pump 81. In this pump water added through a line 77 and complex from the line 75 are contacted and the complex substantially completely decomposed. The products of this decomposition are then passed through a pump discharge line 82 into a settling tank 76 in which the oils and aqueous phases are separated by gravity settling. The lower or aqueous phase from this tank passes through a draw-off line 78 back through pump 81 for recycle. As the aqueous phase in tank 76 builds up, a portion may be discarded through a discard line 83 to such disposal as desired. The amount of aqueous phase withdrawn through line 83 and the amount of water added from line 77 are proportioned in such a manner as to maintain an HCl concentration in the aqueous phase in the settler 76 between the approximate limits of 1 to 8 per cent to minimize emulsifying and precipitation of the aluminum compounds. The upper hydrocarbon phase separating in settler 76 may be withdrawn

through an overhead line 19 and passed into the hydrocarbon stream in line 20, then to a suitable water and/or caustic wash and fractionating system, not shown in this figure.

In some cases a single contacting of hydrocarbon and complex will suffice and in this case the separator 13 may be omitted, water being added directly to the contactor effluent.

The following examples will give a better understanding of the operation of our invention. In these examples the aluminum chloride hydrocarbon complex used was discarded catalyst from an ethylene-isobutane alkylation process and received no special treatment prior to use according to our invention. The heat of hydrolysis of the complex was about 325 calories per gram. The olefin-containing benzene stock was recovered from the effluent of a low pressure high temperature thermal cracking operation in which the charge stock was propane. The benzene concentrate contained about 7 mole per cent olefins as determined by bromine titration.

Example I

Five hundred cc. of the olefin-containing benzene was shaken with 100 cc. of the above described AlCl_3 -hydrocarbon complex, the temperature kept at 160° F. or less during the treatment. The two liquid phases were separated. The upper phase, or hydrocarbon phase, was washed with water and caustic solution, and 331 cc. of washed hydrocarbon recovered substantially free of olefins. The lower phase, or complex phase, was poured on ice and decomposed, 190 cc. of oils being recovered after water and caustic washing.

By fractionation, 88 volume per cent of the hydrocarbon phase was recovered as 96 to 98 per cent benzene free of olefins. From the oils of the complex phase, 55 volume per cent was recovered by fractionation as 96 to 98 per cent benzene free of olefins. This result shows 79 volume per cent of the original olefin-containing benzene charged recovered as 96 to 98 per cent benzene free from olefins. This amounts to about 85 per cent recovery of the benzene charged.

In this example, more complex was used than absolutely necessary. There is a lower limit to the amount of complex necessary to remove the olefins from the benzene, and is determined by the composition of the hydrocarbon to be treated and the nature of the AlCl_3 -hydrocarbon complex.

Example II

A two-stage countercurrent treatment of the olefin-containing benzene with AlCl_3 -hydrocarbon complex was carried out using complex in the amount of five volume per cent of the hydrocarbon treated.

One hundred fifty cc. of the benzene concentrate was treated with complex to reduce its olefin content to about 3-4 per cent, and the complex discarded. Then this hydrocarbon was treated with 7.5 cc. of fresh complex, and the hydrocarbon phase discarded. This latter complex was then used to treat 150 cc. of fresh benzene concentrate; the complex phase from this treatment was saved for evaluation. The hydrocarbon from this treatment was then contacted with 7.5 cc. of fresh complex, the hydrocarbon phase saved for evaluation and the complex phase discarded.

The complex phase saved for evaluation was decomposed with ice and the oils recovered added to the hydrocarbon phase saved for evaluation. These hydrocarbons were then washed with

water several times, and the washed hydrocarbons distilled; 125 cc. of saturated benzene was recovered in this distillation. Based on the benzene content of the benzene concentrate, this is 90 per cent recovery, thus indicating better results from multistage countercurrent treating. This benzene concentrate had a bromine No. of 0.1, thus indicating a product of good quality.

As a comparative example, a batchwise single-stage treatment with five volume per cent complex reduced the unsaturation of the benzene concentrate from 7 to 3.5 per cent.

Equipment for use in our process should possess such corrosion resistant properties as not to be corroded unduly during operational or standby periods. Since water is added to aluminum chloride catalyst, or rather spent catalyst materials, hydrogen chloride is of course produced and this material in the presence of water is quite corrosive. Corrosion resistant equipment to withstand such action is readily available in commerce and, of course, should be used where needed.

Many valves, pressure and temperature indicating devices have not been shown in the drawing nor mentioned in the written description for purposes of simplicity. The installation and use of such equipment is well understood by those skilled in the art.

It will be obvious to those skilled in the art that many modifications of our process may be made and yet remain within the intended spirit and scope of our invention.

Having described our invention, we claim:

1. A continuous countercurrent process for the purification of a hydrocarbon stock containing an aromatic hydrocarbon selected from the group consisting of benzene, toluene and the xylenes, and containing olefinic impurities, for the removal of this olefinic impurity and wherein the hydrocarbon stock remains otherwise substantially unaltered, comprising contacting in a first zone with respect to the flow of complex an aluminum chloride hydrocarbon complex and partially treated hydrocarbon stock containing said aromatic hydrocarbon and olefinic impurities in the ratio of a maximum of about 20 parts by weight of complex to 100 parts by weight of hydrocarbon stock, separating the so treated stock as a product of the process from the contacted aluminum chloride hydrocarbon complex, further contacting this latter complex in a second zone with the first mentioned hydrocarbon stock and with dry hydrogen chloride as an activator wherein the complex is substantially fully degraded and the hydrocarbon stock is partially purified, separating said partially purified hydrocarbon stock from the substantially fully degraded complex and passing said partially purified hydrocarbon stock to the first contacting zone as the partially purified stock; adding water to the substantially fully degraded complex to liberate hydrogen chloride, said liberated hydrogen chloride containing some moisture, and treating said liberated hydrogen chloride containing some moisture with a fresh aluminum chloride hydrocarbon complex to remove said moisture from said hydrogen chloride and passing this dried hydrogen chloride into said second zone as the first mentioned dry hydrogen chloride, and passing said aluminum chloride hydrocarbon complex from the moisture removal step to said first contacting zone.

2. A continuous countercurrent process for the purification of a hydrocarbon stock containing benzene and olefinic impurities for the removal

of said olefinic impurities and wherein the hydrocarbon stock remains otherwise substantially unchanged comprising contacting an aluminum chloride hydrocarbon complex in a first zone with respect to flow of complex and partially treated hydrocarbon stock containing said benzene and some olefinic impurity in the ratio of a maximum of about 20 parts by weight of complex to 100 parts by weight of hydrocarbon stock, separating the so treated stock as a product of the process from the contacted aluminum chloride hydrocarbon complex, further contacting this latter complex in a second zone with the first mentioned hydrocarbon stock and with dry hydrogen chloride as an activator wherein the complex is substantially fully degraded and the hydrocarbon stock is partially purified, separating said partially purified hydrocarbon stock from the substantially fully degraded complex and passing said partially purified hydrocarbon stock to the first contacting zone as the partially purified stock; adding water to the substantially fully degraded complex to liberate hydrogen chloride, said liberated hydrogen chloride containing some moisture, and treating said liberated hydrogen chloride containing some moisture with a fresh aluminum chloride hydrocarbon complex to remove said moisture from said hydrogen chloride and passing this dried hydrogen chloride into said second zone as the first mentioned dry hydrogen chloride, and passing said aluminum chloride hydrocarbon complex from the moisture removal step to said first contacting zone.

3. A continuous countercurrent process for the purification of a hydrocarbon stock containing toluene and olefinic impurities for the removal of said olefinic impurities and wherein the hydrocarbon stock remains otherwise substantially unchanged comprising contacting an aluminum chloride hydrocarbon complex in a first zone with respect to flow of complex and partially treated hydrocarbon stock containing said toluene and some olefinic impurity in the ratio of a maximum of about 20 parts by weight of complex to 100 parts by weight of hydrocarbon stock, separating the so treated stock as a product of the process from the contacted aluminum chloride hydrocarbon complex, further contacting this latter complex in a second zone with the first mentioned hydrocarbon stock and with dry hydrogen chloride as an activator wherein the complex is substantially fully degraded and the hydrocarbon stock is partially purified, separating said partially purified hydrocarbon stock from the substantially fully degraded complex and passing said partially purified hydrocarbon stock to the first contacting zone as the partially purified stock; adding water to the substantially fully degraded complex to liberate hydrogen chloride, said liberated hydrogen chloride containing some moisture, and treating said liberated hydrogen chloride containing some moisture with a fresh aluminum chloride hydrocarbon complex to remove said moisture from said hydrogen chloride and passing this dried hy-

drogen chloride into said second zone as the first mentioned dry hydrogen chloride, and passing said aluminum chloride hydrocarbon complex from the moisture removal step to said first contacting zone.

4. A continuous countercurrent process for the purification of a hydrocarbon stock containing xylene and olefinic impurities for the removal of said olefinic impurities and wherein the hydrocarbon stock remains otherwise substantially unchanged comprising contacting an aluminum chloride hydrocarbon complex in a first zone with respect to flow of complex and partially treated hydrocarbon stock containing said xylene and some olefinic impurity in the ratio of a maximum of about 20 parts by weight of complex to 100 parts by weight of hydrocarbon stock, separating the so treated stock as a product of the process from the contacted aluminum chloride hydrocarbon complex, further contacting this latter complex in a second zone with the first mentioned hydrocarbon stock and with dry hydrogen chloride as an activator wherein the complex is substantially fully degraded and the hydrocarbon stock is partially purified, separating said partially purified hydrocarbon stock from the substantially fully degraded complex and passing said partially purified hydrocarbon stock to the first contacting zone as the partially purified stock; adding water to the substantially fully degraded complex to liberate hydrogen chloride, said liberated hydrogen chloride containing some moisture, and treating said liberated hydrogen chloride containing some moisture with a fresh aluminum chloride hydrocarbon complex to remove said moisture from said hydrogen chloride and passing this dried hydrogen chloride into said second zone as the first mentioned dry hydrogen chloride, and passing said aluminum chloride hydrocarbon complex from the moisture removal step to said first contacting zone.

5. The process of claim 1 wherein the aluminum chloride hydrocarbon complex and the partially purified hydrocarbon stock containing said aromatic hydrocarbon and olefinic impurities are contacted in said first zone in the ratio of about 5 parts by weight of complex to about 100 parts by weight of hydrocarbon stock.
